UNITED STATES PATENT OFFICE

2,351,186

POT TYPE BURNER AND MEANS FOR DELIVERING SECONDARY AIR THERETO

James L. Breese, Santa Fe, N. Mex., assignor to
Oil Devices, Santa Fe, N. Mex., a limited partnership of Illinois

Application July 11, 1941, Serial No. 401,919

3 Claims. (Cl. 158—91)

My invention relates to an improvement in burners and is particularly applicable to pot type burners burning liquid hydrocarbon fuels.

One purpose is to provide improved means for supplying secondary air thereto.

Another purpose is to provide an improved burner and radiating or combustion chamber in which secondary air is supplied to the interior of the combustion chamber.

Another purpose is to provide means for supplying secondary air through the combustion chamber wall.

Another purpose is to provide means for supplying secondary air to cause a swirling or turbulence of the flame.

Other purposes will appear from time to time in the course of the specification.

I illustrate my invention more or less diagrammatically in the accompanying drawing wherein:

Fig. 1 is a vertical axial section;

Fig. 2 is a section on the line 2—2 of Fig. 1;

Fig. 3 is a vertical axial section of a variant form of the device; and

Fig. 4 is a section on the line 4—4 of Fig. 3.

Like parts are indicated by like symbols throughout the specification and drawing.

Referring to the form of Figs. 1 and 2, 1 indicates a base member or shell, which may be upwardly extended, as at 2, to form an upper combustion chamber or radiating drum, which may have any suitable flue connections not herein shown. 3 are any suitable supporting means, legs or the like. 4 is a bottom for the member 1, which is provided with a preferably central air inlet aperture 5. 6 is a flange or ring inwardly extending from an upper portion of the member 1. Mounted on the ring is a pot 7, having a concave bottom 8 and a liquid fuel line 9, controlled by any suitable valve, generally indicated as 10.

It will be realized that any suitable means may be employed for controlling or varying the supply of fuel along said line. I illustrate a conventional manually operable valve, but it will be understood that any other suitable means, automatically or manually controlled, may be employed.

The wall of the pot 7 is provided with a plurality of primary air inlet apertures 11, located at various levels therein. The top of the pot is partially closed by a flame ring 12, having a central aperture 13. The apertures 11 are so sized, spaced and proportioned as to provide an adequate supply of primary air for maximum combustion conditions in the pot.

The secondary air I prefer to supply through

the wall of the combustion chamber 2. I illustrate for example in Figs. 1 and 2, a pair of air inlet passages 14, 15, which are aligned with apertures 16, 17 in the wall of the member 2. Preferably, the members 14 and 15 terminate outside of but close to the outer edge of the aperture 13. A single member 14 or 15 may be employed, but I prefer to employ a pair of diametrically opposed members, as shown in Figs. 1 and 2. These members may be directly radial, but I find it advantageous under some circumstances to tilt them from the radial, as shown in Fig. 2, in order to provide a swirl or vortex of secondary air, which tends to surround the upwardly traveling mixture of primary air and vaporized hydrocarbon which issues through the aperture 13.

It will be understood that the liquid fuel supplied along the line 9 to the bottom 8 of the pot 20 is vaporized by the heat of combustion in or above the pot, and this vaporized hydrocarbon mixes with the primary air to produce a mixture which is completely burned upon the addition of the secondary air. In the low stages, that is, the pilot stage, the lowest air holes may serve the primary air admission function, and the upper air holes may serve as a secondary air supply when combustion takes place in the lower or intermediate part of the pot. However, at the high fire the additional supply of secondary air provided by the inlets 14 and 15 is necessary, and the mixture is completed, and the combustion takes place above the fire ring 12. It will be understood that the height of the fire is controlled simply by controlling the rate of supply of liquid fuel, and the process of combustion is the so-called hydroxylation process, the details of which need not here be considered. I do not wish to be limited to the employment of any specific number of the inlets 14, 15, but the structure shown in Figs. 1 and 2 is practical and operative.

Referring to the form of Figs. 3 and 4, they differ from the form of Figs. 1 and 2 only in the employment, instead of the open ended inlet pipes 45 14, 15, of a distributing head 20, which is preferably located on the vertical axis of the pot. This head 20 may receive its supply of secondary air, for example, through the pipe 21, which is shown as extending from side to side of the drum 2 connecting the apertures 22 and 23 in its side. The passage 21 is connected by a short downward neck 24, with the head 20, and the head is provided with air apertures 25, which serve to direct the supply of secondary air, in this instance downwardly and outwardly, into the mixture of

primary air and vaporized hydrocarbon which rises about the more or less conic distributing head 20. It is under some circumstances advantageous to have the secondary air preliminarily heated prior to its admission to the mixture, and this result is obtained by the employment of the pipe 21, which is subjected to the heat of combustion.

It will be realized that, whereas I have described and illustrated a practical and operative device, nevertheless many changes may be made in the size, shape, number and disposition of parts without departing from the spirit of my invention. I therefore wish my description and drawing to be taken as in a broad sense illustrative or diagrammatic, rather than as limiting me to my precise showing.

The use and operation of my invention are as follows:

I illustrate a so-called hydroxylation burner, in which a primary mixture of air and vaporized liquid hydrocarbon is formed, and then has added to it a supply of secondary air to complete combustion. It has been customary in pot type burners to add secondary air by means of inlet passages or apertures in the wall of the pot itself.

I find it desirable to employ a pot type burner in which a combustion or radiation chamber is associated which is above and in communication with the interior of the pot and through the walls of which the secondary air may be admitted. In the particular form shown in Figs. 1 and 2 I find it desirable to incline the inlet tubes 14, 15 from the radial in order to cause the flame to spiral.

It will be understood that it is practical also to have the tubes directly opposed and at any desired angle. Also, the number of tubes may be varied.

The velocity and direction of the secondary air are of prime importance in the flame formation and placing, and the spiraling effect obtained by the form of Figs. 1 and 2 is advantageous. I obtain a different but also highly practical flame control in the form of Figs. 3 and 4, in which the primary mixture flows upwardly and outwardly about the cone 20 and receives the downwardly and outwardly directed secondary air through the outlets 25.

Referring to the form of Figures 1 and 2, it will be observed that the axes of the ducts 14 and 15 are for convenience generally parallel. Both axes are offset from a radial line extending from the center of the pot to the center of the outlet aperture 16 or 17. For convenience I have described this relationship in the claims as inclination from the radial meaning inclination of the ducts 14 or 15 in relation to a line extending radially from the center of the pot to the center of the outlet aperture in the shell 2 with which the duct 14 or 15 is in communication.

I claim:

1. In a pot type heater, an outer housing, a

burner pot located in a lower portion of said housing, a closure extending from an upper portion of the pot to the housing, the pot having a plurality of primary air inlet apertures located at various levels in its wall, a centrally apertured flame ring partially closing the top of the pot, a closed bottom for the pot and means for delivering a liquid fuel to the interior of the pot, and means for delivering secondary air to the mixture of primary air and vaporized fuel rising from the pot which includes a plurality of tubes inwardly extending from the wall of the outer housing and terminating at a level above the top of the pot and adjacent the aperture in said flame ring, the interior of said tubes being in communication with outside air, said tubes being provided with an air delivery aperture located adjacent the aperture in said flame ring the axis of each said tube extending toward the pot, but being inclined in relation to a radius extending from the center of the pot to the inlet end of such tube.

2. In a pot type heater, an outer housing, a burner pot located in a lower portion of said housing, a closure extending from an upper portion of the pot to the housing, the pot having a plurality of primary air inlet apertures located at various levels in its wall, a centrally apertured flame ring partially closing the top of the pot, a closed bottom for the pot and means for delivering a liquid fuel to the interior of the pot, and means for delivering secondary air to the mixture of primary air and vaporized fuel rising from the pot which includes a tube inwardly extending from the wall of the outer housing and terminating at a level above the top of the pot, the interior of said tube being in communication with outside air, said tube being provided with an air delivery aperture located adjacent the aperture in said flame ring the axis of said tube being inclined in relation to a radius extending from the center of the pot to the inlet end of the tube.

3. In a pot type heater, an outer housing, a burner pot located in the lower portion of said outer housing, a closure extending from an upper portion of the pot to the housing, the pot having a plurality of primary air inlet apertures located at various levels in its wall, a centrally apertured flame ring, which partially closes the top of the pot, a closed bottom for the pot, means for delivering a liquid fuel to the interior of the pot, and means for delivering secondary air to the mixture of primary air and vaporized fuel rising from the pot, which includes a pair of air delivery tubes extending inwardly from the side of the outer housing and terminating above the flame ring and adjacent its central aperture, the axes of said tubes being generally parallel, and being offset from each other, the axis of each tube being inclined to a radius extending from the center of the pot to the inlet end of the tube.
